UNITED STATES PATENT OFFICE.

CYRUS CALVIN ROSE, OF BLAIR TOWNSHIP, WASHINGTON COUNTY, NEBRASKA.

HARNESS ATTACHMENT.

971,644.

Specification of Letters Patent.

Patented Oct. 4, 1910.

Application filed January 14, 1910. Serial No. 538,017.

To all whom it may concern:

Be it known that I, CYRUS CALVIN ROSE, citizen of the United States of America, residing in Blair township, in the county of 5 Washington and State of Nebraska, have invented certain new and useful Improvements in Harness Attachments, of which the following is a specification.

My invention relates to improvement in 10 that part of a harness where the hames are coupled together at the top and the spread-reins are supported; and the objects of my improvement are, first, to provide a coupling for the tops of hames rendering them more 15 closely adjustable to the length of the collar; second, to facilitate supporting the opposed inward bends of the top ends of the side-halves of horse collars, especially those made open at the top; third, to provide a 20 support for the rein spread-strap at a high point on the hame; fourth, to combine the lock for the hame adjustment with the spread-strap support to simplify the whole; and, fifth, to provide an attachment readily 25 fitted and fastened to hames now in use; all of which with other objects of minor importance I attain by the mechanism illustrated by the accompanying drawing in which—

30 Figure 1 is a front elevation of the whole contrivance applied to a harness; Fig. 2, is a horizontal section on the broken line *a* of Fig. 1, showing the top of the collar carrying the hame; Fig. 3, is a side face view of 35 the toothed adjusting-plate or bar before it is attached to the hame; and Fig. 4, is an out side face view of the closing-plate detached; in all of which views similar numerals refer to like parts.

40 On an ordinary wooden hame 2 having the out-edge metal facing-strap or back-iron 3, I illustrate my attachment applied, as shown in Figs. 1 and 2. The notched bar 4 has a longitudinal base fitted to the facing iron 3; for this fitting it is cross-concaved 45 on the back as shown in Fig. 2, and is made of ductile metal so that it may be bent to fit hames curved at the top as shown. Its outer face is toothed to form the vertical 50 row of notches 6, 6 etc. and the lower end

tooth 19 is tapered and extended downward longitudinally—as shown in Fig. 3—to form a cold-shut to close through the loop 8 in the lower end of the closing-plate 7 to hinge said closing-plate to said notched bar. The 55 notched bar has the perforations 18 and 18 to receive screws as indicated at 17 and 17 or other suitable means to fasten it to the hame, on which it is disposed above but close to the usual rein-ring 10. The upper end of 60 the notched bar has the chape-loop 5 disposed to project through the slot 9 at the top end of the hinged closing-plate when it is swung against the notched bar to close the notches 6 to retain the ring 15 at the desired adjustment.

The spread-strap 11 looped into the terminal ring 14 to carry the spread-rein 26, has its buckled end 13 inserted through said chape-loop by which it is supported, and 70 where it serves as a key or cotter 12 to lock the closing-plate closed against the notched bar.

The link or ring 15 through which is 75 looped one end of the top hame-strap 16, is preferably a full circle of diameter much larger than a cross-section of the hame; in any case, either by size or some modified form, it is made of backward and forward extension sufficient to overlap and give full 80 bearings 23 and 24, on the after-wale 20 and fore-wale 21 of the collar 25; as shown in Fig. 2, and in Fig. 1 where the relative position of the collar is indicated by the broken lines 22. This support preserves the curvature of the top ends of the collar-sides and thereby preserves the pressed form of the neck-pad so that it is not broken, distorted 85 or galling.

The curved broken line *b* in Fig. 1 indicates the sweep of the top end of the closing-plate when it is released by removing the cotter 12 from the loop 5 and is opened to shift the ring to different notches to attain the desired adjustment of the length of the 95 hames to fit the collar.

I claim:

A harness attachment, comprising a multi-notched ductile bar adapted to be bent to fit and fastened on a hame to engage a link 100

on a hame-strap, a notch-closing plate having a hinge-loop and a slot, a cold-shut on the bar closed through said hinge-loop, a chape-loop on the bar disposed to project 5 through the slot in the closed plate to receive and support a spread-strap to lock said plate.

In testimony whereof I affix my signature in presence of two witnesses.

CYRUS CALVIN ROSE.
